UNITED STATES PATENT OFFICE.

HOSFORD D. KELLOGG, OF HAVERFORD, PENNSYLVANIA.

DESIGN FOR A RADIATOR.

53,018.

Specification for Design.

Patented Feb. 25, 1919.

Application filed November 20, 1918. Serial No. 263,432. Term of patent 14 years.

To all whom it may concern:

Be it known that I, HOSFORD D. KELLOGG, a citizen of the United States, and a resident of Haverford, county of Delaware, and State of Pennsylvania, have invented a certain new, original, and ornamental Design for Radiators, (the mechanical details of this type of radiator being broadly covered by pending application, Serial No. 95,581, filed May 5, 1916,) as shown in the accompanying drawings, in which—

Figure 1 is a perspective view of a radiator embodying the new design and as viewed

from in front of the same, Fig. 2 is a similar view of the radiator as viewed from the rear of the same, and Fig. 3 is a fragmentary rear elevation of the same.

I claim:

The ornamental design for a radiator substantially as shown.

In witness whereof, I have hereunto set my hand this 19th day of Nov., A. D. 1918.

HOSFORD D. KELLOGG.
